UNITED STATES PATENT OFFICE.

HENRY W. HIRSCHFELD, OF MERIDEN, CONNECTICUT, ASSIGNOR TO THE
MERIDEN BRITANNIA COMPANY, OF SAME PLACE.

DESIGN FOR A SPOON, &c.

SPECIFICATION forming part of Design No. 21,383, dated March 8, 1892.
Application filed February 1, 1892. Serial No. 419,995. Term of patent 7 years.

To all whom it may concern:

Be it known that I, HENRY W. HIRSCHFELD, of Meriden, in the county of New Haven and State of Connecticut, have invented a new Design for the Handles of Spoons and Forks; and I do hereby declare the following, when taken in connection with accompanying drawing, to be a full, clear, and exact description of the same, and which said drawing constitutes part of this specification, and represents a face view.

This invention relates to a design for the ornamentation of the handles of spoons, forks, and like articles; and it consists in the shape and ornamentation as shown in the accompanying illustration. The handle from about midway of its length gradually expands by

serpentine curved sides to the end, where it terminates in a rounded shape. The edges of the handle, following the said serpentine sides, represent an ornamentation of rococo-work running up each side and meeting at the center top, as shown in the accompanying illustration.

I claim—

The design for the handles of spoons and forks, as herein shown and described.

In testimony whereof I have signed this specification in the presence of two subscribing witnesses.

HENRY W. HIRSCHFELD.
